WRINGER

Walter L. Kauffman II, Erie, Pa., assignor to
 Lovell Manufacturing Company, Erie, Pa., a
 corporation of Pennsylvania

Application October 16, 1935, Serial No. 45,280

13 Claims.

(Cl. 68—32)

Wringers as now produced are largely formed from sheet metal or metals having thin walls. It is common to make the top bar of the wringer detachable from the side stiles, both for the purposes of assembly and of providing a safety release for relieving pressure on the rolls. The pressure to which the top bar is subjected in exerting pressure on the rolls requires a rugged securing means between the top and the side stiles and this is difficult to form in the metal commonly used. The present invention is designed to improve the interlocking attachment between the top bar of the wringer stiles.

Features and details will appear from the specifications and claims.

A preferred embodiment of the invention is illustrated in the accompanying drawing as follows:

Fig. 1 shows a front elevation of the wringer, partly in sections to better show construction.

Fig. 2 shows a section on the line 2—2 in Fig. 1.

Fig. 3 shows a central section of the end of the top bar and the top of one of the stiles on the line 3—3 in Fig. 4.

Fig. 4 shows a section on the line 4—4 in Fig. 1.

Fig. 5 shows a perspective view of the end of the top of the stile with the top detached from the stile.

Fig. 6 shows an end elevation of the top of the stile.

Fig. 7 shows a section of the end of the top bar and top of the stile showing a modification of the shoulder forming lip.

Fig. 8 shows a section of the end of the top bar at the top of the stile showing a further modification of the shoulder forming lip.

The wringer frame is made up of base 1 and side stiles 2 and 3, these side stiles being of box form in cross section. The top bar 4 is mounted on the stile. The wringer rolls 5 and 6 are provided with shafts 7 and 8. The lower shaft 8 is journaled in the bearing 9. The bearing 9 rests on a mounting 10 and the mounting 10 rests on shoulders 11 struck in the side walls of the stiles. The upper shaft 7 is provided with a bearing 12 which is slidingly mounted in the stile. The lower shaft 8 is driven from the power shaft 13, receiving power from any desirable source. Spring 14 rests on the top bearings 12, and a screw 15 operates on the top bar to adjust the pressure of the spring.

The top bar is of channel form with closed ends,

the closure forming downwardly extending walls overlapping the outer faces of the stiles.

A release device is provided for one end of the top bar. The latch 16 is formed with side plates 17 united by a cross plate 18. The two side plates of the latch are arranged on each side of the stile. Each plate has a triangularly shaped opening 19 into which extends pivotal lips or lugs 20 struck up from the side wall of the stile, thus pivotally securing the latch on the stile. The latch plates 17 have the latch hooks 21 at their upper ends and these hooks are adapted to engage in turn trunnion plates 22, these plates being formed on the bottom edge of the releasing lever 23. The trunnions 22 extend into the triangular openings 24 in the side walls of the top bar 4, the releasing lever having side plates extending downwardly on each side of the top bar and outside of the latch 16, so that the trunnions pass under the hooks and into the openings 24 in the top bar. A spring 23a normally holds the lever 23 in its set position. The latch 16 is provided with shoulders 25 which engage the outer edges of the trunnions 22, so that with the lever 23 in set position, the latch 16 can become unhooked, but when the outer end of the lever 23 is raised by depressing the inner edge of the lever, the outer edges of the trunnions 22 are lifted above the hooks 21 and this permits the hooks 21 to slide off the trunnion and release the top bar. This particular release mechanism forms no part of this invention, and the parts so far described have been previously formed.

The closed wall of the opposite end of the top bar is secured to its stile as follows:

A lip 26 is bent outwardly from the top of the outer wall of the stile. The outer ends of this lip are connected with the wall of the stile above the lip by webs 27, thus the lip at its front and rear edges are braced, but inasmuch as these edges receive the principal part of the strain, the lip forms a very secure and strong shoulder. The under surface of the lip which is the engaging surface of the shoulder is smooth, so that when the top is released, the disengagement from the under surface of the shoulder is not obstructed.

The top bar is placed over the upper ends of the stile, the top bar telescoping these ends. The end wall of the top bar has an outwardly extending stabbing 28 forming the shoulder 29 under the stabbing. This shoulder 29 is adapted to engage the under face of the lip 26, the interlocking being accomplished by tilting the oppo-

site ends of the top bar and bringing the shoulders 29 under the lips 26, then swinging the free end of the bar downwardly into its normal latched position through the releasing mechanism.

5. In order to strengthen the end wall of the top bar under the shoulder 29, I prefer to provide a bridge piece 30 between the end wall and the stabbing 28. The lip 26 is slotted at 31 to accommodate the bridge piece 30.

10. With this structure, when the end release is operated, the top bar swings up under the impulse of the spring as indicated in Fig. 3 and the shoulder 29 moves outwardly upon the shoulder formed by the lip 26 and is released. The lip may be 15 formed with a return bend as shown at 32 in Fig. 7, may extend at right angles to the face of the stile as shown at 33 in Fig. 8, or may be slightly upwardly inclined as shown in Figures 20 1 to 6. In any event, the engagement with the lip is on a smooth surface which does not obstruct the free outward movement or disengaging movement when the release has been operated.

It is preferable to supply a locking shoulder on the top bar which will engage the inner face of 25 the stile and thus prevent any accidental disengagement of the interlocking shoulders between the top bar and the stile through the springing of the stile under strain. This is accomplished in the present structure by striking 30 up shoulders 34 in the side walls of the top bar. These shoulders 34 are so placed that when the top bar is in a set or normal position, this shoulder engages the inner face of the stile and thus prevents any inward springing of the stile 35 and any disengaging of the interlocking shoulders 26 and 29 without the upswinging of the top bar. This up-swinging carries the locking shoulder 34 above the top of the stile and thus permits of the proper end movement to free the top bar 40 from the interlocking shoulders.

What I claim as new is:

1. In a wringer, the combination of a frame comprising hollow metal stiles, one of the stiles at least having a lip bent outwardly from the top of 45 the stile to form a shoulder, the lip having a web at its edges joining the wall of the stile with the lip; and a top bar having a downwardly extending end wall overlapping the outer face of the stile and having a shoulder engaging the under side of the lip.

2. In a wringer, the combination of a frame comprising hollow metal stiles, one of said stiles at least having a lip bent from the bottom of the lip outwardly to form a shoulder, the lip having 55 webs at its edges joining the wall of the stile above the lip with the lip; and a top bar having a downwardly extending wall overlapping the outer face of the stile, having an outwardly extending stabbing forming a shoulder under the 60 stabbing engaging the shoulder formed by the lip, said stabbing being bridged at its center and the lip having a cut-out portion to accommodate the bridge.

3. In a wringer, the combination of a frame 65 comprising hollow metal stiles one of said stiles at least having a lip bent from the bottom of the lip outwardly to form a shoulder, the lip having a web at its edge joining the wall of the stile above the lip with the lip; a top bar having a 70 downwardly extending end wall overlapping the outer face of the stile and having a shoulder engaging the under side of the lip; and a locking shoulder on the top bar engaging the stile and holding the shoulders at the outer face of the 75 stile against disengagement.

4. In a wringer, the combination of a frame comprising hollow metal stiles, one of said stiles at least having a lip bent from the bottom of the lip outwardly to form a shoulder, the lip having a web at its edge joining the wall of the stile above the lip with the lip; a top bar having a downwardly extending end wall overlapping the outer face of the stile and having a shoulder engaging the under side of the lip; a locking shoulder on the top bar engaging the stile and holding the shoulders at the outer face of the stile against disengagement; and a safety release device for the opposite end of the top bar.

5. In a wringer, the combination of a frame comprising hollow metal stiles, one of said stiles at least having a lip bent from the bottom of the lip outwardly to form a shoulder, the lip having a web at its edge joining the wall of the stile above the lip with the lip; a top bar having a downwardly extending end wall overlapping the outer face of the stile and having a shoulder engaging the under side of the lip; and a locking shoulder on the top bar engaging the inner face of the stile and locking the shoulders at the outer face of the stile against disengagement, said shoulder being fixed and adapted to swing clear of the stile with an up-swing of the opposite end of the top bar.

6. In a wringer, the combination of a frame comprising side stiles; a top bar having a downwardly extending end wall overlapping the outer face of a stile, said wall and the overlapped stile having interlocking shoulders; and a locking shoulder on the top bar engaging the stile and holding the shoulders at the outer face of the 35 stile against disengagement.

7. In a wringer, the combination of a frame comprising side stiles; a top bar having a downwardly extending end wall overlapping the outer face of a stile, said wall and the overlapped stile having interlocking shoulders; and a locking shoulder on the top bar engaging the stile and holding the shoulders at the outer face of the stile against disengagement, said shoulder being fixed and adapted to swing clear of the stile with an 45 up-swing of the opposite end of the bar.

8. In a wringer, the combination of a frame comprising side stiles; a top bar of channel form arranged on the stiles, one end of the top bar having the end closed and forming a downwardly 50 extending wall overlapping the outer face of the side stiles, the side walls of the top overlapping the side faces of the stile; locking shoulders between the overlapping end wall and the stile; and a locking shoulder struck up in the side wall 55 of the top bar and engaging the stile, holding the interlocking shoulders against disengagement.

9. In a wringer, the combination of a frame comprising hollow metal stiles, at least one of said stiles having a lip bent so that it extends upwardly and outwardly of the stile to form a shoulder; and a top bar having a downwardly extending end wall overlapping the outer face of the stile and having a shoulder engaging the under side of the lip.

10. In a wringer, the combination of a frame comprising hollow metal stiles, at least one of said stiles having a lip bent so that it extends upwardly and outwardly of the stile to form a shoulder; webs at the ends of the lip joining the lip with the stile; and a top bar having a downwardly extending end wall overlapping the outer face of the stile and having a shoulder engaging the under side of the lip.

11. In a wringer, the combination of a frame 75

- comprising hollow metal stiles, at least one of said stiles having a lip bent so that it extends upwardly and outwardly of the stile to form a shoulder; webs at the ends of the lip joining the lip with the stile, said web extending above the lip; and a top bar having a downwardly extending end wall overlapping the outer face of the stile and having a shoulder engaging the under side of the lip.
12. In a wringer, the combination of a frame comprising hollow metal stiles, at least one of said stiles having a lip bent so that it extends upwardly and outwardly of the stile to form a shoulder; a top bar having a downwardly extending end wall overlapping the outer face of the stile and having a shoulder engaging the under

- 10
- 15

side of the lip; and a safety release for securing the opposite edge of the top bar.

13. In a wringer, the combination of a frame comprising hollow metal stiles, at least one of said stiles having a lip bent so that it extends upwardly and outwardly of the stile to form a shoulder; and a top bar having a downwardly extending end wall overlapping the outer face of the stile and having a shoulder engaging the under side of the lip, said top bar and frame having engaging surfaces locking the top bar when in normal position against endwise movement disengaging the shoulder on the top bar from the lip.

WALTER L. KAUFFMAN II. 15
